Application August 15, 1934, Serial No. 739,971

15 Claims. (Cl. 255—73)

The invention is designed to provide an enlarging bit for enlarging the hole made by an earth boring drill.

The invention consists in the features and combination and arrangement of parts herein-after described and particularly pointed out in the claims.

In the accompanying drawings:

Figure 1 is a side view of the apparatus with parts in section.

Fig. 2 is a bottom plan view partly in section on line 2—2 of Fig. 1 with the spindle and cutter assemblies omitted.

Fig. 2a is a top plan view of the head.

Fig. 3 is a side view of the bit head slightly turned from the position of Fig. 1 and with the spindle and cutter assemblies omitted.

Fig. 4 is a side view of a cutter spindle and its carrier bracket or support.

Fig. 5 is a plan view of Fig. 4 looking in the direction of the arrow 5 in Fig. 4.

Fig. 6 is a face view of the spindle and its support looking from the left of Fig. 5.

Fig. 7 is a sectional view of a thrust plate.

Fig. 8 is a central vertical sectional view taken in a diametrical plane of the axis of the applicance.

In these drawings *a* is the body portion of the enlarging bit or head. It has an upper substantially cylindrical portion *1* which is screw threaded internally for attachment to the drill stem or pipe. It has at its lower end an externally screw threaded portion as at *3* for attachment to a drill.

Extending laterally from an intermediate zone of the body are protuberant portions comprising arms or flanges *4*, *4*. These are recessed at *4a*. These arms are bifurcated at their lower ends presenting downwardly and outwardly extending forked formations *5*, the arms of which are continuations of the arms *4*, *4* and the spaces between the sides of the forked formations being continuations of the recesses between the said arms or flanges *4*, *4*.

These forks and the flanges of which the forks form extensions overhang the main body of the tool. They lie outwardly in respect to the side of the main body of the tool, and their general relation to the main body is at an outward and downward inclination.

The forks present on their sides or edges which face the main body of the tool inclined edges at *6* against which bears the flange *7* of a support or carrier for roller cutter means. I show, desirably, a pair of roller cutters *8*, *9* for each fork

construction of which there are three spaced 120° apart around the bit head or body.

These cutters are mounted on spindles, one of which is shown at *10*, the axis of which extends outwardly and upwardly in respect to the vertical axis of the bit head. The spindle is integral with its support or carrier which comprises in addition to the flange *7* above mentioned, a body portion *7a* having its outer face *7b* at a sharp inclination to the plane in which the base flange *7* lies so that when the support is mounted in the fork *5* overhanging the side of the body of the bit head, the flange will bear on the inclined inner surface or edge of the fork while the outer edge or face *7b* of the support will extend substantially vertically and parallel with the wall of the bore hole being drilled. The outer edge or face *5a* of the overhanging fork also extends vertically parallel with the outer face *7b* of the bracket or support for the roller cutter, but it will be noted that the face *7b* lies out beyond the face *5a* and the adjacent part of the body of the cutter support or bracket serves as a guard to take wear that otherwise would be imposed on the fork member itself. The lower end of the body *7a* also projects below the lower end of the fork and thus protects it from wear. The carrier or support *7a* for the spindle has a shank *7c* which extends upwardly from the body portion substantially parallel with the plane in which the flange *7* lies, or in other words this shank extends at right angles to the axis of the spindle. It rests in the recess *4a* between the flanges or arms extending laterally beyond the side of the body of the bit head and the said shank is held in place desirably by welding as indicated at *b*, Fig. 1. The shank projects slightly as at *7d* beyond the outer edges of the arms or flanges of the head, it being understood that the carrier bracket may be renewed by cutting out the weld with a suitable torch. By reason of the construction described, involving the laterally protuberant arms with its flanges and the forks overhanging the side of the bit head body, the bracket when in place, together with the welded joint thereof, is exposed laterally of the bit head and is thus readily accessible. The shank portion of the spindle carrying bracket is of less width than the diameter of flange *7* so that said flange finds a bearing against the inner side of the arms or forks *5* to take the radial thrusts and also to some extent the upthrusts. The latter thrusts, however, are taken mainly by the shoulder *7e* of the bracket, which shoulder bears upon a shoulder *11* located at the base of the fork arms *5*.

5 or in other words, at the lower end of the bottom wall of the recess 4a of the lateral arms or protuberances from the bit head. Ball bearings 12 are employed between the roller cutters 8 and the spindle, and roller bearings 13 are used between said spindle and the other cutter 9. In order to support the inner end 10a of the spindle a thrust plate 14 receives the spindle end 10a which latter is of smaller diameter than the main part of the spindle, thus presenting a thrust shoulder at 10b.

This thrust plate has a portion 14a which fits into the open side of the adjacent cutter and provides a closure at this point for the raceway of the anti-friction rollers.

The other side of the raceway is provided by a flange 8a of the roller cutter 8.

The thrust plate is welded to the main body portion of the bit head.

20 The construction disclosed herein enables the spindle and cutter assembly to be handled as one unit in connecting the same with the head or removing it therefrom. That is to say, the spindle with its bracket, the roller cutter means, 25 and the thrust plate are all assembled while apart from the bit head and are then placed in connection therewith as one body, preferably by welding.

As before stated, there are three such units. 30 They are placed 120° apart around the bit head. Their cutters track each other and enlarge the hole cut by another drill organization whether this be an entirely separate drill or a drill mounted on the same drill stem or pipe in advance of the said enlarging drill.

The drill has a central bore for the passage of flushing fluid, and suitable ports lead off from this bore to distribute the said fluid to the cutters. One of these ports is shown at x.

40 The weld which holds the thrust plate to the bit head can be cut out by a torch so that the cutter assembly can be removed from the bit head.

The ball bearings are of comparatively large 45 size. They take drilling loads and end thrusts. They bear on the base flanges of the spindles as well as on the spindles themselves.

The roller bearings take thrusts imposed radially of the cutter axis. They are not intended 50 to take end thrusts imposed parallel with the cutter axis.

The body of the bit head has an inclined face 1a against which the thrust block bears.

The downwardly and outwardly extending protuberances or arms of which the flanges 4, 45 form a part are braced or reinforced by web-like formations 15b which flare outwardly and downwardly from the body of the tool. These webs or reinforcements for the overhanging arms 60 are integral with the body of the tool and lie between the spaced apart arms.

These webs are integrally united with arms more particularly at the lower forked ends of said arms. These web-like reinforcing formations 65 are connected at their portions lying midway of the spaces between the arms or protuberances with ribs 15a forming integral downward extension of the said webs, said ribs being integrally connected with the body portion of the tool. The web formation is formed with recesses or arches 15d through which recesses the roller cutters project as shown in Fig. 1. This construction just described provides an enlargement intermediate the upper and lower ends of 70 the comparatively small diameter main body por-

tion, which enlargement is of the general shape of a frustum of a cone, the side of which is slabbed off presenting vertically disposed flat surfaces 15e. Viewed in plan view, Figs. 2 and 2a the webs are slightly concaved in shape, leaving 5 the overhanging forked arms, the parts with the maximum protrusion from the vertical axis of the drill. These webs not only brace the forked arms, but they leave ample clearance space between the tool and the side of the hole, for flow 10 of flushing fluid. The cutters are preferably frusto-conical with their projected apices beyond the vertical axis of the drill. The outer edges of the webs, Figs. 2, 2a, are virtually chords of arcs of a circle touching the outer ends of the 15 protuberant arms.

I claim:

1. A hole enlarging bit head for drilling wells comprising a central body having a plurality of arms spaced apart around said body and inclining downwardly and outwardly beyond said central body, said arms having recessed seats for roller cutter supports, and webs disposed outwardly from said central body and extending between and connecting the arms. 20

2. A bit head according to claim 1 in which the webs extend outwardly from the bit head to a point to connect the outermost ends of the arms. 25

3. A hole enlarging bit head according to claim 1 in which the web between adjacent arms is connected with a rib arranged intermediate the adjacent arms, said rib being connected with and projecting outwardly from the central body of the drill. 30

4. An enlarging bit for drilling wells comprising a body with a plurality of outwardly and downwardly projecting arms with a laterally open recess in each arm, a rotary toothed cutter for each arm and a support for each rotary cutter comprising a spindle on which the cutter is mounted, and a shank inclining upwardly and inwardly towards the vertical axis of the bit, and secured in the laterally open recess of the arm, said cutters tracking each other over an annular 45 path adjacent the side of the bore hole and outwardly from a bore hole of smaller diameter previously formed, said cutters being mounted laterally in respect to the body of the bit, substantially as described. 50

5. An earth boring tool of the character described comprising a body portion, an arm projecting outwardly and downwardly from said body, and having an exterior seat, a spindle having a body portion seated in the arm, and a shank extending from said body portion at an angle to the axis of the spindle and fitted to said exterior seat, said spindle having a free end adjacent the body of the bit, a removable thrust plate at the free end of the spindle bearing on the body of the bit, a plurality of roller cutters on the spindle arranged side by side and contacting each other, roller bearings between the innermost cutter and the spindle and ball bearings of comparatively large diameter between 65 the outermost cutter and the spindle and its support, said ball bearings taking the end thrust of the cutters, substantially as described. 60

6. A bit head comprising a main central body having spaced apart protuberances extending laterally beyond the sides of said body and inclining downwardly, and terminating at their lower outer ends in forked portions, said protuberances having exteriorly open recesses extending at an upward and inward inclination towards the vertical 70 75

axis of the head, webs flaring outwardly and downwardly from the central body of the head intermediate and connected to the said protuberances and bracing the forked portions of the same, said forked portions of the protuberances having their under faces inclining upwardly and inwardly towards the vertical axis of the head, and having their outermost faces extending substantially vertically, the bottom of the exterior recesses in 5 the protuberances also inclining upwardly and inwardly towards the vertical axis of the drill.

10. A spindle for a roller cutter of an earth boring drill having a base flange, a portion of a ball bearing raceway partly on said spindle and 15 partly on said flange, a body portion integral with said base flange and beyond the sides of which the base flange extends, and a shank extending from said body portion parallel with the plane in which the base flange lies at right angles 20 to the axis of said spindle.

8. A spindle according to claim 7 in which the outer face of the body portion extends at an inclination to the said shank and flange and extends between the two, substantially as de- 25 scribed.

9. A spindle according to claim 7 in which the body portion has a thrust shoulder lying in a plane parallel with the axis of the spindle and between the plane of the flange and the shank, 30 substantially as described.

10. A hole enlarging bit comprising a body having laterally extending portions from which roller cutter unit assemblies are suspended below and rigidly held by said portions and positioned 35 outwardly from said main body, spindles mounting in said assemblies roller cutter means and roller bearings between said laterally extending portions and the body of the bit, said spindles having flanges and shanks engaging said laterally extending portions, reinforcing webs connecting said portions with the main body intermediate the assemblies, a thrust plate at the free end of each spindle anchored to the body 40 exteriorly thereof, each spindle extending at an inclination downwardly and inwardly in respect to the vertical axis of the bit and positioned exteriorly of said body, the body of said bit having an inclined surface in a plane at right angles to the spindle axis for seating each thrust plate, 45 said thrust plates furnishing a bearing for the end of each spindle, for the ends of the roller bearings and for a cutter and supported on the said inclined surface of the bit body.

11. A hole enlarging bit comprising a main body having laterally and downwardly projecting portions overhanging its side, said portions being reinforced laterally thereof by flaring webs

connecting said portions with bulging, integral, bridging sections of the body positioned intermediate said portions and said sections connecting the upper and lower ends of said body, spindles supported exteriorly of said body by said 5 overhanging portions, and roller cutter means on said spindles cutting an annular path inclined to the axis of the body.

12. A hole enlarging bit comprising a main body having laterally and downwardly projecting 10 portions overhanging its side, said portions being reinforced laterally thereof by flaring webs connecting said portions with the body intermediate said portions, spindles supported exteriorly of said body by said overhanging portions, and 15 roller cutter means on said spindles cutting an annular path inclined to the axis of the body.

13. A hole enlarging bit according to claim 12, the roller cutter means in sections, roller bearings between one section and the spindle and ball 20 bearings between another section and the spindle and also contacting a bearing area positioned on the spindle support taking end thrusts of the cutter means.

14. A bit head for a bore hole enlarging tool 25 comprising a central body portion having three arms spaced 120 degrees apart around the periphery of the bit head, said arms projecting downwardly and outwardly from said central body and forming cutter receiving recesses be- 30 tween the overhanging arms and the lower part of the body portion, said arms having seat recesses formed therein for receiving roller cutter supports, and webs disposed outwardly from said central body and extending between and con- 35 necting the outer portions of the arms to each other and to the body to brace the arms.

15. An enlarging bit comprising a substantially cylindrical body portion, arms projecting outwardly and downwardly therefrom and overhanging the lower part of said body portion, said arms being three in number spaced 120 degrees apart about the body, the width of the arms at their outer faces being considerably less than the 40 distance between the arms measured along the chords extending between them, said arms being recessed, and roller cutter supports having shanks held in the recesses of the arms and having roller cutter spindles extending from their 45 lower ends downwardly and inwardly towards the body and webs extending from the body and connecting with the outer ends of the arms there being spaces above the webs and between the upper ends of the arms, substantially as de- 50 scribed.

CLARENCE E. REED.
